[57] CLAIM

The ornamental design for a bottle crate, as shown and described.

DESCRIPTION

FIG. 1 is a side elevation view of a bottle crate showing my new design, the opposite side being the same in appearance;

FIG. 2 is an end elevational view, the opposite end being the same in appearance;

FIG. 3 is a top plan view;

FIG. 4 is a bottom plan view;

FIG. 5 is a sectional view of the left half of the bottle crate taken on the line 5—5 of FIG. 2, the right half being a mirror image thereof; and

FIG. 6 is a section view of the left half of the bottle crate the right half being a mirror image thereof.

Fig. 4

FIG. 6.

FIG. 5.
